METALWORKING TOOL

Paul Rekettye and Carl A. Maxwell, Akron, Ohio,
assignors to The Babcock & Wilcox Company,
Rockleigh, N. J., a corporation of New Jersey

Application February 7, 1946, Serial No. 646,074

7 Claims. (Cl. 77—2)

1

The present invention relates to improvements in metal working tools, and more particularly to tools for refacing the seats for the covers used in effecting pressure tight closure of handhole or access openings in vessels included in the pressure parts of vapor generating equipment and similar apparatus normally operating under a substantial pressure.

The customary cover seat for a handhole opening in a steam boiler steam or water header, for example, is a machine finished plane surface on the inside face of the header wall, the surface being annular and normal to the edge walls of the handhole opening. The complementary cover extends over the handhole and is bolted against the seat by external means to provide a fluid tight joint between the seat and the cover.

When in the course of operating service the seat becomes pitted or scored by the action of the fluid in the header, or is otherwise marred or damaged in a manner which might hinder the attainment of fluid tight contact between the cover and seat, it is necessary that one or both of the co-acting surfaces be refinished. No great difficulty is experienced in refinishing the handhole cover since it can be removed from the header, but refacing the seat on the inner wall of the header, in the field, is difficult, and a compact, accurate and readily mountable tool is of particular advantage in facilitating the seat refacing work.

Heretofore various types of fly-cutters and grinders have been suggested for such seat refacing work, but they have been considered inadequate due to the required methods of support, difficulty of insertion and withdrawal from the handhole opening and the uncertainty of tool position control.

It is therefore the main object of the present invention to provide a portable seat refacing tool assembly capable of field use in accurately refacing the inner wall seats surrounding openings in pressure vessels. Another and more specific object is to provide a simple and compact tool assembly of the character described capable of being mounted in a position closely associated with the surface to be refinished. A further specific object is to provide apparatus for refacing the handhole seat in a boiler or economizer header or the like which is characterized by its ability to be manually adjustable for depth of cut while the radial position of the cutting tool is maintained in the desired width of cut responsive to a fluid pressure. A further specific object is to provide a device for refacing a handhole

2

seat wherein the cutting tool associated therewith is retractable from its cutting position for ease of installation and removal of the device.

The various features of novelty which characterize our invention are pointed out with particularity in the claims annexed to and forming a part of this specification. For a better understanding of the invention, its operating advantages and specific objects attained by its use, reference should be had to the accompanying drawings and descriptive matter in which we have illustrated and described a preferred embodiment of our invention.

Of the drawings:

15 Fig. 1 is an elevation of a handhole seat refacing tool constructed in accordance with the present invention and in operative position with respect to a header handhole;

Fig. 2 is a plan view of the apparatus shown 20 in Fig. 1;

Fig. 3 is an elevation, largely in cross-section, taken on the line 3—3 of Fig. 2;

Fig. 4 is a cross-section of the apparatus taken on the line 4—4 of Fig. 3; and

25 Fig. 5 is a cross-section of the apparatus taken on the line 5—5 of Fig. 3.

In the drawings, a tool assembly constructed in accordance with the present invention is illustrated in position to refinish the seat 10 of a handhole 11 in the wall 12 of a boiler or economizer header. The header in which the handhole is located may be circular in transverse cross-section, or it may be square or of other shape without altering the general method of tool support and operation hereinafter described. The handhole 11 and handhole seat 12, as indicated in Fig. 2, are of the conventional elliptical shape to permit the entrance and seating of an elliptical shaped handhole cover which is held in position by external clamps (not shown) in a well known manner.

The machine in general includes a shaft or spindle 14 projecting through the handhole opening and rigidly supported in a position normal to the plane of the handhole seat 10 and centrally positioned relative to the handhole opening. A hub 15 is rotatably mounted on the spindle 14 and arranged to support and position a refinishing or cutting tool 16 in contact with the seat 10. The hub is constructed to provide a radial movement of the tool into proper cutting position in response to pneumatic pressure, while an adjustment of the tool 16 for the desired depth of cut is accomplished by a

manual adjustment of the hub 15 along the axis of the spindle 14.

As shown in the drawings, the outer end of the spindle 14 is supported by a frame 17 bearing on the exterior of the header wall 12 and straddling the handhole, while its inner end is supported by a clamp 18 having two diametrically opposite arms bearing on the interior surface of the header wall and also straddling the handhole. An opening 20 in the central portion of the frame 17 fits the outer end of the spindle which has a projecting reduced threaded section 21 and a machined shoulder 22, so that a lock nut 23 tightly drawn against the shoulder also rests upon the outer surface of the frame. The spindle projects through the handhole into the header and has a threaded end section 24 in the clamp 18. With the nut 23 in place on the shoulder 22, the frame 17 and clamp 18 are drawn into position abutting the outer and inner surfaces of the header wall 12 by screwing the spindle into the clamp through the use of a wrench engaging a socket 25 in the outer end section 21 of the spindle.

It will be observed that with the construction described the outer end of the spindle 14 is maintained in a fixed relation within the frame 17 while any change in the thickness of the header wall for different handholds will cause a corresponding axial change in the position of the clamp 18 on the inner end 24 of the spindle. The advantage of this construction are described hereinafter.

The hub includes a rotatable spacer 26 of cylindrical shape having a hollow interior threaded to engage a correspondingly threaded feed sleeve 28. A girth gear 27 mounted on the upper portion of the spacer 26 is arranged to receive and transmit rotational movement to the hub assembly. The lower portion of the spacer 26 is provided with a socket 30 of rectangular cross-section arranged to support and guide the movement of a tool holder or plunger 31 of rectangular cross-section in a direction normal to the axis of rotation of the spacer. This socket is formed with an open bottom, closed by a removable cover plate 32, and an open end in one side of the spacer through which the plunger 31 projects in radially guided movements. The socket and plunger can also be made of circular cross-section, if desired.

The central portion of both the cover plate 32 and a transverse partition 33 which defines the top wall of the socket 30 are machined to provide an opening for the press fit therethrough of a bearing sleeve 34. The bearing sleeve has an internal bore adapted to rotatably fit the spindle 14. Within the upper portion of the spacer the sleeve 34 is extended to engage in a sliding fit with a bushing 35 which is pressed into one end of the feed sleeve 28.

The feed sleeve 28 is spaced from the inner side of the frame 17 by a bronze washer 36 and is further provided with a ball type thrust bearing 37 inserted between an annular shoulder on the spindle 14 and an annular internal shoulder on the upper end of the feed sleeve 28. In the assembly of the hub described, the spacer 26 and the feed sleeve 28 are mounted for rotation about the spindle 14, with the feed sleeve rotating in a fixed axial position relative to the spindle as determined by the washer 36 and the thrust bearing 37. While the spacer 26 also rotates with the feed sleeve about the spindle 14, its axial position relative to the spindle may be manually

adjusted by relative rotation between the spacer and the feed sleeve by means of the threaded connection therebetween. During such an axial positioning of the spacer, the bearing sleeve will move longitudinally with the spacer between the spindle 14 and the bushing 35 so that the concentricity of both the feed sleeve 28 and the spacer 26 will be maintained. The circumferential surface of the outer end of the sleeve 28 is knurled, as shown in Fig. 1, so that the axial adjustment of the spacer 26 may be made by hand rotation thereof or by rotation with the aid of a pin (not shown) inserted in an opening 28'.

A rotational movement is transmitted to the hub assembly through the girth gear 27 by a meshing pinion 38 on a jack shaft 40. The jack shaft is rotatably mounted in a bearing sleeve 41 of bronze or the like, inserted in an opening 20 through the frame 17 and spaced at one side of the spindle 14 so that the axis of the jack shaft is parallel to the axis of the spindle. The bearing sleeve 41 is open on its side adjacent the spindle from a position intermediate its height to the bottom thereof, to permit gear and pinion engagement throughout the axial length of hub 15 adjustment. The open portion of the sleeve 41 as shown has an angular extent of approximately 95°. The upper end of the jack shaft is formed with a square cross-section to fit a corresponding wrench (not shown), used in the manual rotation of the tool. Alternately a slow speed air motor or other mechanical or electrical device may be used to transmit rotational force thereto.

As shown in Fig. 3, the pinion 38 which is essentially the same diameter as the shaft 40 is provided with a threaded neck for attachment in a correspondingly threaded cavity in the lower end of the shaft 40, and a washer 42 is attached to the lower end of the pinion by a screw 43. The outside diameter of the washer 42 is slightly less than either the pinion or shaft. The difference in diameter need be only a few hundredths of an inch, so as to provide rotational clearance between the washer and the bearing sleeve 41. Thus, when the teeth of the gear 27 and pinion 38 are in operative engagement the teeth of the gear are overlapped on top and bottom by the end of the shaft 40 and the washer 42 so that the gear and pinion will remain in mesh regardless of the axial position of the spacer 26 on the spindle 14 and the shaft 40 cannot be withdrawn through the bearing sleeve 41.

Referring particularly to Figs. 3 and 4, the plunger 31 is of rectangular cross-sectional shape having a rounded end 44 and with its sides, top and bottom finished to close tolerances for a snug, sliding fit in the socket 30. Since the bearing sleeve 34 extends through the central portion of the socket 30, the plunger 31 is provided with a longitudinally elongated opening 45 therethrough which determines the limits of radial movement of the plunger 31 by the clearance between the walls of the opening and the sleeve 34. The rounded end 44 of the plunger is provided with a recess 46 of square cross-section for the support of the cutting tool 16 which is held therein by a laterally extending set screw 47. The recess 46 is located in the plunger so that the cutting edge of the tool inserted therein will be located along the longitudinal centerline of the plunger and perpendicular to the axis of rotation of the tool 16 about the spindle 14. A transverse slot 48 is located immediately above the recess 46 in the

end of the plunger for the installation of a roller 50. The roller 50 is rotatable about a vertically positioned pin 51 which is so spaced along the longitudinal axis of the plunger with regard to the end 44 that a segment of the roller projects beyond the plunger 31. While the projection of a segment of the roller beyond the end of the plunger is fixed at all times, the extent of the projection of the cutting tool 16 beyond the plunger may be altered as required to regulate the width of the cut of that tool on the seat 10 of the handhole. The opposite end of the plunger 31, within the socket 30, is provided with an aperture 52 connecting the elongated opening 45 surrounding the spindle 14 with the socket 30.

A fluid under pressure, for example, compressed air, is delivered to the socket 30 through a series of internal passageways as shown in Figs. 2, 3, 4, and 5. Compressed air is delivered to the apparatus through a flexible hose or the like (not shown) which is connected to an opening 55 in one side of the frame 17 adjacent the spindle. This opening extends through the wall of the frame 17 and is in communication with an annular groove 56 in the surface of the spindle from which a diametrical hole 57 leads to an axial bore 58 therein. Above the level of the hole 57, the bore 58 is cut to a larger diameter, threaded and then sealed by a flat pointed set screw 60.

The axial bore 58 extends approximately to the midpoint of the spindle and at this point a diametrical hole 62 connects the bore 58 with a pair of longitudinal grooves 63 in the outer surface of the spindle. These grooves 63 are parallel to the axis of the spindle and extend a distance substantially equal to the extent of axial adjustment of the spacer 26 on the spindle 14. A vertically spaced pair of annular grooves 64 in the internal surface of the sleeve 34 are each provided with a pair of radially drilled holes 65 and 66 through the wall of the sleeve leading respectively to the elongated opening 45 in the plunger 31 and to the upper portion of the spacer 26 above the partition 33. Thus, regardless of the axial position of the spacer relative to the spindle 14, compressed air will be delivered to the elongated opening 45, and the passage of the air through the aperture 52 into the rear of the socket 30 will force the plunger radially outward.

When the spacer 26 is in a proper position relative to the handhole opening 11 and the seat 10, the action of the compressed air in forcing the plunger outward will bring the roller 50 in contact with the wall 12 and the tool 16 in contact with the seat 10. The compressed air acting on the plunger 31 will cause it to slide outwardly in the socket 30 maintaining the roller 50 in contact with the wall 12, and as the hub 15 is rotated about the spindle 14 the roller follows the contour of the handhole wall correspondingly changing the radius arm of the tool 16. The slight leakage of compressed air between the walls of the plunger 31 and the socket 30 will advantageously prevent the deposition of metal chips therebetween from the machining operation. This will avoid scoring and undue wear on those surfaces.

In the installation of the apparatus described, the plunger 31 with its associated roller 50 and cutting tool 16 is retracted into the socket 30 and the clamp 18 is adjusted to a position on the inner end 24 of the spindle 14. The apparatus may then be tipped to one side and the clamp and spindle inserted in the handhole 11. With the frame 17 resting on the exterior surface of the

wall 12 and the spindle 14 projecting through the handhole in its desired axial position, the clamp may be drawn into tight contact with the inner surface of the handhole wall by turning the spindle. Thus the spindle is rigidly positioned relative to the handhole seat with the seat refacing tool desirably mounted between the spindle end supports. Thereafter a preliminary axial adjustment of the spacer 26 is made to assure contact of the roller 50 upon the wall 12 of the handhole when the plunger 31 is radially extended by the application of compressed air thereto. It is of course understood that the preliminary adjustment of the level of the plunger 31 so that the roller 50 will be in contact with the handhole wall when radially extended must necessarily position the tool 16 so that it will project into the annular recess in the handhole wall beneath the seat 10. The cutting tool 16 may then be brought into a cutting contact position with the seat 10 by axial adjustment of the spacer 26, and as the tool is rotated by turning the jack shaft 40, the depth of cut on the surface of the seat is regulated by further adjustment with the feed sleeve 28.

After completing the seat refacing operation, the tool assembly is removed from the handhole by releasing the compressed air pressure, relieving the holding pressure of the clamp 18 by unscrewing the spindle 14 and tipping the assembly for withdrawal through the handhole opening. With the removal of the compressed air pressure on the plunger 31, the plunger is free to move in its socket 30 and it may be manually retracted so that the projection of the tool 16 beyond the body of the spacer 26 is at a minimum, thereby facilitating the removal of the apparatus from the handhole.

It will be observed that the retractability of the cutting tool assembly within the hub of the apparatus contributes materially to the facility of installation and removal thereof prior and subsequent to the machining operation. The use of a pressure fluid and a guide roller to radially position the cutting tool so as to follow the contour of the handhole advantageously provides a substantially uniform application of radial pressure thereon and assures an accurately machined seat. Furthermore, since the tool assembly of the present invention is completely supported in the one handhole and all adjustments of the tool and tool assembly may be accomplished either through that handhole or externally of the header, it is not necessary to support the tool assembly from an adjacent handhole or handhole fitting, or to open an adjacent handhole for access to the inner end of the tool assembly.

While in accordance with the provisions of the statutes we have illustrated and described herein in the best forms of our invention now known to us, those skilled in the art will understand that changes may be made in the form of the apparatus disclosed without departing from the spirit of the invention covered by our claims, and that certain features of our invention may sometimes be used to advantage without a corresponding use of other features.

We claim:

1. A tool assembly for machining an internal closure seat for a pressure vessel wall opening comprising a spindle arranged to project through said pressure vessel wall opening, means for supporting said spindle normal to the plane of the

closure seat and substantially centered with respect to the wall of said opening, a spacer journaled for rotation about said spindle, a radially slideable tool holder mounted within said spacer, a metal cutting tool and a roller mounted in spaced relationship in said holder and arranged to project radially beyond one end of said holder, means for rotating said spacer about said spindle, means for adjusting the position of said spacer axially of said spindle, and means for pneumatically adjusting said holder radially of said spindle with said roller in guiding contact with the boundary wall of said pressure vessel opening.

2. A tool assembly for machining an internal closure seat for a pressure vessel wall opening comprising a non-rotative spindle arranged to project through said opening normal to the plane of said seat, means providing a rigid support for said spindle on opposite sides of said handhole wall, a spacer arranged for rotation upon said spindle, a threaded sleeve rotatable with and engaging corresponding threads within said spacer, a thrust bearing arranged to position said sleeve relative to said spindle and to permit axial adjustment of the spacer on said spindle, a plunger slidably fitted within a radial open ended socket in said spacer, said plunger having an elongated opening therethrough loosely encircling a portion of said spindle, a cutting tool mounted within a receptacle of said plunger and arranged to project beyond the end thereof, a guide roller mounted in a recess of said plunger arranged to project beyond the end of said plunger and in inwardly radial spaced relationship with said cutting tool, means responsive to a fluid pressure for holding said guide roller in contact with the internal configuration of said wall opening, and means for rotating said spacer.

3. A tool assembly for machining an internal closure seat for a pressure vessel wall opening comprising a non-rotative spindle arranged to project through said wall opening normal to the plane of said seat, means providing a rigid support for said spindle on opposite sides of said handhole wall, a spacer arranged for rotation upon said spindle, a threaded sleeve rotatable with and engaging corresponding threads within said spacer, a thrust bearing arranged to position said sleeve relative to said spindle, a plunger slidably fitted within a radial open ended socket in the bottom portion of said spacer, said plunger having an elongated opening therethrough loosely encircling a portion of said spindle, a cutting tool mounted within said plunger and arranged to project beyond the end thereof, a guide roller mounted in a recess of said plunger arranged to project beyond the end of said plunger and in inwardly radial spaced relationship with said cutting tool, means associated with said spindle and said spacer for transmitting a gaseous fluid pressure to said socket for urging said plunger radially outward for contact between said roller and the wall of said pressure vessel opening, and means for rotating said spacer.

4. A tool assembly for machining an internal closure seat for a pressure vessel wall opening comprising a frame arranged to exteriorly straddle said wall opening, a spindle threaded at both ends arranged to project through said opening and said frame in a direction normal to said closure seat, a lock nut threaded to the exterior end of said spindle and arranged to position the end of the spindle relative to said frame, a clamp

arranged to interiorly straddle said wall opening and threaded upon the interior end of said spindle, a spacer arranged for rotation upon said spindle, a threaded sleeve rotatable with and engaging threads within said spacer, a thrust bearing arranged to fix the axial position of said sleeve relative to said spindle, a radially slideable plunger within said spacer, a cutting tool and a roller in spaced relation therewith secured to said plunger and arranged to project radially normal to and beyond the cylindrical wall of said spacer, means for rotating said spacer and said sleeve about said spindle, and means for radially adjusting said plunger with its cutting tool into contact with said seat.

5. A tool assembly for machining an internal closure seat for a pressure vessel wall opening comprising a frame arranged to exteriorly straddle said wall opening, a spindle threaded at both ends arranged to project through said opening and said frame in a direction normal to the closure seat and substantially centered with respect to the wall opening, a lock nut threaded to the exterior end of said spindle and arranged to position the end of the spindle relative to said frame, a clamp arranged to interiorly straddle said wall opening and threaded upon said spindle, a hub arranged for rotation upon said spindle, a threaded sleeve rotatable with and engaging corresponding threads within said hub, a thrust bearing arranged to fix the position of said sleeve relative to said spindle, a plunger slidably fitted within a radial open ended socket in the bottom portion of said hub, a cutting tool mounted within said plunger and arranged to project beyond the end thereof in a plane parallel to the plane of the closure seat, a guide roller mounted in a recess of said plunger in radially spaced relationship with said cutting tool, means associated with said spindle and said hub for transmitting a fluid pressure to said socket urging said plunger radially outward for engaging contact between said roller and the wall of said pressure vessel opening, and means for rotating said hub.

6. A tool assembly for machining an internal closure seat for a pressure vessel wall opening comprising a spindle arranged to project through said opening, a frame arranged to support said spindle normal to the plane of the closure seat and centrally located with respect to the wall opening, a generally cylindrical spacer arranged for rotation on said spindle and having a bearing sleeve affixed thereto encircling said spindle, a cylindrical threaded sleeve in fixed axial position relative to said spindle rotatable with and engaging corresponding threads internally of said spacer, a radially slideable plunger within said spacer, a cutting tool and a roller in spaced relation therewith secured to said plunger and arranged to project radially normal to and beyond the cylindrical wall of said spacer, means for rotating said spacer about said spindle, and means for radially adjusting said plunger with its cutting tool in contact with said seat including an axial bore extending longitudinally of said spindle from a radial opening adjacent the outer end of said spindle and communicating with a source of compressed air to a radial opening intermediate the length of said spindle, a longitudinal groove in the surface of said spindle extending inwardly from said intermediate opening, and internal circumferential grooves on said bearing sleeve having radial openings leading from said grooves to a recess behind said plunger in said spacer.

7. A tool assembly according to claim 1 where-
in said means for supporting said spindle com-
prises a frame exteriorly straddling said wall
opening and embracing the exterior end of said
spindle, and a clamp having arms straddling the
interior of said wall opening and threaded upon
the interior portion of said spindle.
